CLAIM

The ornamental design for a dart, substantially as shown and described.

DESCRIPTION

FIG. 1 is a perspective view of a dart embodying our new design;

FIG. 2 is an enlarged view which can be either a top plan view, a side elevational view from either side, or a bottom plan view;

FIG. 3 is a front end view of the dart, taken from the left end as viewed in FIG. 2;

FIG. 4 is a rear end view thereof, taken from the right end as viewed in FIG. 2; and

FIG. 5 is a transverse sectional view taken as indicated by the arrowed line 5—5 of FIG. 2.

FIG. 1.

FIG. 2.

FIG. 3.

FIG. 4.

FIG. 5.
